To all whom it may concern:

Be it known that I, JAMES P. HOOPER, a citizen of the United States of America, and resident of Ruxton, county of Baltimore, State of Maryland, have invented a certain new, original, and ornamental Design for Padding, of which the following is a specification.

The figure is a plan view of a piece of the padding, a small portion at the edges being turned for convenience of illustration. The material shown consists of parallel juxtaposed strands 1, 2, 3, etc., of cotton or similar roving held in the foresaid relation by means of a knitted mesh work 4 arranged in the manner illustrated.
